UNITED STATES PATENT OFFICE.

ALFRED G. F. KUROWSKI, OF BROOKLYN, NEW YORK, ASSIGNOR TO UNDERWOOD
ELLIOTT FISHER COMPANY, OF NEW YORK, N. Y., A CORPORATION OF DELAWARE.

TYPEWRITING MACHINE.

Application filed January 9, 1926. Serial No. 80,164.

This invention relates to a decimal tabulating key mechanism for typewriting machines, and one of its main features is the facilitating of the manipulation of tabulating keys by the expedient of differentiating the key which is most used from the other keys.

Some typewriters are equipped with a set of decimal-keys which release the carriage and are also effective to arrest the same at selected denominational positions. In the present invention, advantage is taken of the fact that, when a long series of tabulating operations is performed, most of the items thereof have the same number of digits, as, for instance, when tabulating gas or electric bills, most of which are for amounts between one and nine dollars.

This invention is especially adapted to machines having depressible key-levers which are placed in a row in front of the keyboard, such as occur in the well-known Underwood standard typewriter.

Sometimes, in order to make the machine more adaptable to the requirements of different establishments, it is desired to provide means whereby any one of the tabulating keys may be readily set to be actuated by the operation of a palm-key. According to one form of the invention, in which this idea is carried out, there is provided a cross-shaft overlying the key-levers which shaft is provided with an arm setably mounted thereon. Said arm is designed to engage the top of the selected key and to depress the same upon actuation of the palm-key which is operatively connected to the shaft.

According to another form of the invention, means are provided for operating the first tabulating key by means of a palm-key which may be placed at the left-hand side of the keyboard. One of the features of this form of the invention relates to the constructional features of the device which adapts it to be built as a unit, to be attached to any standard machine without even necessitating the drilling of any holes in the frame thereof.

According to still another form of the invention, there is provided an actuating lever which is swung by means of a palm-key and may be extended to press either the first or the second tabulating key. In this form, advantage is taken of the fact that usually

either the first or the second tabulating key is used more than the other keys, since they represent the highest denominational column, which permits the operative to move the carriage to its exact position by operating the space-bar.

A further advantage of this invention relates to its adaptability to be used in connection with the Underwood combined typewriting and computing machine in which the keys, owing to certain well known constructional features of the machine, are sometimes hard to depress. By means of this invention the depression of the key which is most usually operated is considerably lightened, thereby improving its touch which is desirable.

Other features and advantages will hereinafter appear.

In the accompanying drawings,

Figure 1 is a front elevation, partly in cross-section, and shows the invention as applied to an Underwood standard typewriting machine.

Figure 2 is a plan view of Figure 1 showing the palm-key actuating on the first tabulating key.

Figure 3 is a cross-sectional view in elevation through the line 3—3 of Figure 2.

Figure 4 is a cross-sectional view through the line 4—4 of Figure 1, and shows the first tabulating key in its operative position.

Figure 5 is a similar view showing the palm-key in effective position.

Figure 6 is a perspective view showing the rock-shaft-actuating means, and the key-operating arm.

Figure 7 is a front view, partly in cross-section, of a modified form of the invention, and shows means for operating either the first or the second tabulating key.

Figure 8 is a plan view of the modified form shown in Figure 7.

Figure 9 is a cross-sectional view in elevation through the line 9—9 of Figure 8.

Figure 10 is a cross-sectional view showing the modified form of the invention in which provision is made for operating the first key.

Figure 11 is a side view of the modification shown in Figure 10.

This invention is illustrated as applied to an Underwood standard typewriting machine, in which a plurality of depressible tabulating keys 10 are arranged in a row in

front of the keyboard. The mechanism, which is operated by the depression of the tabulating keys, broadly consists in releasing the carriage of the machine, and in arresting the same in any of a plurality of denominational positions. This mechanism is not shown in this invention because the same is well standardized in the Underwood machine.

10 It is one of the main features of this invention to selectively depress any one of the keys 10 by the operation of a palm-key 11, which is placed for the convenience of the operator at the left-hand side of the machine. According to the preferred form of this invention, there is provided a shaft 12 which overlies key-levers 13, and is journaled in brackets 14 which are fast to the frame 15 by means of screws 16. The shaft 20 is operatively connected to the palm-key 11 by means of a cam-plate 18 which is fast to the palm-key by means of rivets 17. Said plate 18 is pivotally mounted on a stud 19, the plate being designed to engage the under side of a roller 20 which is secured to the shaft 12 by means of a screw 21. It will be seen that, by depressing palm-key 11 to the dot-and-dash position shown in Figure 1, the shaft 12 will be swung, and, since 30 there is provided a rearwardly-extending arm 22 fast to the shaft 12 by means of a screw 23, the lever 13 underlying the arm 22 will be depressed, thus releasing and arresting the carriage. In order to facilitate 35 the engagement of the arm 22 with the lever 13, and to eliminate friction, there may be provided a roller 24 which may be rotatably mounted on a shouldered screw 25 fast to the arm 22. In Figures 4 and 5, the operated and inoperated positions of the first 40 tabulating key are shown, the relative positions of the arm 22 and the roller 20, which are both fast to the shaft 12, being shown in Figure 6.

45 According to a modified form of the invention, there is provided mechanism for operating either the first or the second tabulating key by means of a palm-key 26. Said form is illustrated in Figures 7, 8 and 9, and 50 comprises a lever 27 pivotally mounted on a stud 28 which is fast to the frame 15. One side of the lever 27 is designed to engage a roller 29 mounted on the key-lever 13 by means of a bracket 30, the latter being secured to the key-lever by means of screws 31. The other side of the lever 27 is engaged at the under side thereof by means of a pin 32 fast to a bracket 33 which forms 55 an integral part of the palm-key 26 and is 60 rotatably mounted on a supporting stud 34 fast to the frame 15. For convenience in manufacturing, it may be desired to make the palm-key 26 separate from the bracket 33, in which case the two are attached together by means of rivets 35, as shown in

Figure 7. In order to actuate the second key, the lever 27, which is shown in dot-and-dash lines in Figure 7, is cut out at 36, so as to clear the first tabulating key, thereby permitting the unobstructed operation of the 70 second tabulating key.

Usually it is only necessary to operate the first tabulating key which represents the highest denominational column, in which case numbers having less digits are typed 75 by spacing the carriage by means of the space-bar. In order to suit this condition, and in order that the device may be supplied to be attached to a standard machine, another form of the invention has been devised and is illustrated in Figures 10 and 11. In this modification it is proposed to provide a U-shaped bracket 37 designed to straddle the left-hand side-bar frame of the machine to which the bracket is secured by 80 means of screws 38. In order to reinforce said bracket 37 there is provided, at the bottom thereof, a plate 39 which serves as a spacer between the open ends of the bracket 37. Said plate 39 is held in place by means 85 of screws 40 and serves as a means for receiving a screw 41, which engages the under side of the frame and forces the bracket downwardly to be squared against the top of the frame. It will be noted that by means 90 of this construction a rigid bracket may be attached to the machine without any machining thereto. Said bracket is provided with an inwardly extending arm 42, which carries a supporting stud 43 upon which a 100 lever 44 is rockably mounted. A palm-key 45 is fast to a supporting stud 46 by means of a screw 47, said stud being journaled in an inwardly extending bracket 48 which is bent out of the bracket 37 and forms an integral part thereof. Said stud 46 protrudes outwardly to one side of the bracket 48, and carries fast thereto an arm 49 which extends downwardly and inwardly and carries a pin 50 at the end thereof designed 105 to engage a slot 51 in the lever 44, thus providing a positive connection between said arm 49 and said lever 44, so that when the palm-key 45 is depressed the first tabulating key will also be depressed by means of 110 the herein-described train of connections. In order to restore the palm-key to its normal position after each depression, there is provided a spring 52 which may actuate between the lever 44 and a supporting stud 53, the latter being fast to the bracket 37. The travel of the key is limited by means of a pin 61 which is carried by the bracket 37.

In order that the palm-key 11 may be held in its normal position, there is provided a 125 restoring spring 54, which may be arranged to actuate between the plate 18, to which it is secured at 56, and a tab 57 which may form an integral part of the brackets 14. The travel of the palm-key is limited by means 130

of a tab 55 which strikes the frame 15. For convenience in manufacturing, said tab 55 may form an integral part of the plate 18.

The means for controlling the travel and the restoring of the palm-key 26, illustrated in Figure 7, is accomplished by means of spring 59 which forces the palm-key to its normal position, in which it is held by means of a bent tab 58, forming an integral part 10 of the bracket 33. Said spring 59 is wound around the stud and actuates between the lever 27 and a fixed point, which may be the frame of the machine.

Variations may be resorted to within the 15 scope of the invention, and portions of the improvements may be used without others.

Having thus described my invention, I claim:

1. The combination, in a typewriting machine, of a series of depressible denominational tabulating keys, a cross-shaft overlying the tabulating keys, a palm-key, means for operatively connecting the shaft to the palm-key in a manner to rock the shaft when 25 the palm-key is operated and settable means on the shaft for selectively depressing one of the tabulating keys when the shaft is rocked.

2. The combination, in a typewriting machine, of a series of depressible denominational tabulating keys, a cross-shaft overlying the tabulating keys, a palm-key, means for operatively connecting the palm-key to the shaft in a manner to rock the shaft upon 35 depression of said palm-key, and an arm settable mounted on the shaft in a manner to depress a selected tabulating key by the rocking action of the shaft.

3. The combination, in a typewriting machine, of a series of depressible denominational tabulating keys, a shaft overlying the tabulating keys, fixed brackets in which the shaft is journaled, a palm-key, means for operatively connecting the palm-key to the 45 shaft in a manner to rock the latter upon operation of the former, and settable means for operatively connecting the shaft to one

of the keys, so that the selected key will be operated when the shaft is rocked.

4. The combination, in a typewriting machine, of a series of depressible denominational tabulating keys, a rock-shaft overlying the keys, fixed brackets for supporting the shaft, a roller on said shaft, a palm-key, an extension on said palm-key for engaging said roller, so as to rock the shaft upon depression of the palm-key, an arm settable upon said shaft, and a roller mounted on said arm in a manner to engage and depress a tabulating key upon rocking the 60 shaft.

5. The combination, in a typewriting machine, of a series of depressible denominational tabulating keys, a rockably mounted palm-key, a rock shaft journaled in fixed 65 brackets, means for operatively connecting said palm-key to the shaft in a manner to rock the shaft when the palm-key is operated, and settable means for operatively connecting said shaft to a selected one of the 70 tabulating keys in a manner to depress the latter upon rocking of the shaft.

6. In a typewriter tabulating mechanism, the combination of a series of denominational tabulating keys, a palm-key, an actuator operated by said palm-key and extending along said series of denominational keys, and a device settable along said actuator to be controlled by the palm-key and to operate any tabulating key to which it is set. 75

7. In a typewriter tabulating mechanism, the combination of a series of denominational tabulating keys, a palm-key, an actuator operated by said palm-key and extending along said series of denominational 85 keys, and a device settable along said actuator to be controlled by the palm-key and to operate any tabulating key to which it is set, said actuator in the form of a rock-shaft, and said settable device in the form of an 90 arm mounted upon said shaft to rock therewith and slidable along the shaft for engagement with any denominational key.

ALFRED G. F. KUROWSKI.
